INVENTOR.
Charles C Hansen
BY *Herbert H. Lyden*
HIS ATTORNEY

UNITED STATES PATENT OFFICE.

CHARLES C. HANSEN, OF EASTON, PENNSYLVANIA, ASSIGNOR TO INGERSOLL-RAND COMPANY, OF JERSEY CITY, NEW JERSEY, A CORPORATION OF NEW JERSEY.

TRENCH DIGGER.

Application filed August 2, 1927. Serial No. 210,185.

This invention relates to shoveling or excavating machines but more particularly to that type of shoveling machine known as a trench digger.

5 It is an object of this invention to facilitate the digging of trenches or other excavation work automatically and preferably by pneumatic or pressure fluid means lessening the manual labor usually employed for such 10 operations.

This and other objects are accomplished by providing a wheeled machine capable of being pushed forward by a single operator and completely operated by him from his 15 normal position at the rear of the machine. By a very slight effort on the part of the operator comparatively large quantities of material may be removed at each operation, the shoveling portion of the machine being 20 forced into the material to be removed by pneumatic percussive means and removed as well by pneumatic devices. The material thus loaded on the shovel and raised is automatically swung laterally and dumped or 25 thrown to the side by means which cooperates with the lifting devices.

The invention will be more clearly understood by referring to the drawings which illustrates an improved form which the 30 invention may assume in practice.

In the drawings,

Figure 1 is the top view of an excavating machine constructed in accordance with the practice of the invention.

35 Figure 2 is a view of the shovel emptying mechanism taken on the line 2-2 of Figure 1 looking in the direction indicated by the arrows.

Figure 3 is a longitudinal sectional elevation of the valve chest taken on the line 40 3-3 of Figure 1 looking in the direction indicated by the arrows.

Figure 4 is a side elevation of the trench 45 digger party in section showing the shovel in place in the trench, and

Figure 5 is a view similar to Figure 4 showing the shovel at the moment of emptying.

Referring more particularly to the draw-

ings A designates the frame of the machine 50 in this instance built of steel channel beams B securely tied together by cross pieces C. The frame A is mounted on wheels D carried by an axle E which supports the upright angle bars F to which the channel 55 beams B are fastened. A shoe G is carried at the lower end of an upright H which is braced by slanting members J secured to the shoe G and the forward end of the carriage A. Handles K are provided for moving 60 the machine from place to place and for the convenience of the operator.

A shovel L is mounted on the end of a rod O which is secured in a pneumatic hammer P and the whole shovel mechanism is 65 slung in place in a novel manner. A yoke Q secured to the shovel handle carries lever arms R and R' to which are attached chains S and S' leading to other lever arms T and T'. The lever arms T and T' are mounted 70 on a suitable supporting bar U mounted in bearings V which are secured to the rigid parts of the machine. To ring W in the rearward end of the shovel handle are fastened chains X which are then fastened to 75 the frame members at J.

A collar Y having an eye Z is located at the forward end of the shovel handle O and a cable b is attached to the eye Z. A lever arm c is mounted on a pin d which is secured 80 in the frame of the machine. A pulley f having a sheave g is mounted on a pin h which is likewise secured to the frame of the machine.

Crosspieces j fixed to the frame bars B in 85 any suitable manner provide a base for a cylinder k. Mounted in the cylinder k is the piston o having a piston rod p which passes thru a suitable hole q in plate r which closes the forward end of the cylinder k. Mounted 90 on the forward end of the piston rod p is a pulley s having a sheave t rotatable on a pin u. The rearward end of cylinder K is closed by a plate v pierced by an aperture w thru which extends a rod x which slidably 95 fits the aperture w. A bell crank y mounted on the frame of the machine at z has one arm 3 connected to the rod x by a pin 5 and

the other arm 4 connected to the link 6 by a pin 7. The link 6 is rigidly attached to the lever arms T and T' by arm 34.

A valve chest 8 mounted on the cylinder 5 k is supplied with pressure fluid thru hoses 9 and 10, the supply in hose 9 being under constant pressure during the operation of the machine. A piston 11 having a head 12, a larger head 13 and a reduced central portion 14 operates a D valve 15. The piston 11 is slidably mounted in the valve chest, the heads 12 and 13 fitting cylinders 16 and 17 respectively, cylinder 17 being closed by a head 18. The reduced central portion 14 of 10 the piston 11 is adapted to fit securely over the D valve 15 and as the piston reciprocates the D valve alternately opens and closes an inlet passage 19 which communicates with the cylinder k. The D valve 15 15 also controls an exhaust passage 20. An enlargement 21 on the valve chest 8 is bored to form a passage 22. Passages 23 and 24 provide communication between the passage 22 and a valve chamber 25 and the cylinder 25. 17 respectively.

The rod x which projects into the rearward end of the cylinder also passes thru a guide 26 mounted on the frame of the machine. A helical spring 27 is mounted on 30 the rod x between the guide 26 and an enlarged shoulder 28 on the rod x.

The supply of pressure fluid to the machine is controlled by suitable throttle valves 29 and 30 under the control of the 35 throttle levers 31 and 32 respectively. The pneumatic hammer P, which may be one of several well known types, is supplied with pressure fluid thru a hose 33 and this supply is under the control of the valve 30, the cylinder supply in hose 10 being controlled by valve 29.

To understand the operation of the machine assume the shovel L to be in the position shown in Figure 5. The operator then 45 opens the valve 29 and pressure fluid entering the cylinder 17 forces the piston 11 forward thus permitting pressure fluid in the forward end of cylinder k to exhaust to the atmosphere thru passages 19 and 20, the D valve 15 functioning so as to provide a connecting passage between passages 19 and 20. As the pressure fluid starts to exhaust from the cylinder to k the weight of the shovel L acting thru the cable b and the pulley sheaves g and t pulls the piston o forward and the shovel L falls to its position as shown in Figure 4. At this point the operator opens the valve 30 and pressure fluid starts the pneumatic hammer P and the shovel is driven forward under the clay or other substance to be shoveled. Throttle valve 29 is then closed permitting the pressure fluid in the valve chamber to force the piston 11 rearwardly thus opening the passage 19. The piston o is then forced rearwardly by

the incoming pressure fluid and the piston rod p drawn into the cylinder thus drawing up the rope b, swinging the lever arm c upward and raising the shovel with its load of earth. As the piston o rapidly approaches 70 the rearward end of the cylinder k it strikes the projecting rod x forcing it outwardly against the resistance of the spring 27. The bell crank y is attached at one arm end to the rod x and the backward movement of 75 the rod x causes the bell crank to turn on its axis tending to compress link 6 which link acting thru the arm 34 tightens chain S' and tends to relieve tension in chain S thus 80 tilting the shovel and emptying its contents. 80

One great advantage of this shoveling machine is found in its lightness and simplicity since the average workman soon learns how to handle the machine and a skilled operator is not essential to its efficient use. 85

I claim:

1. An excavating machine comprising a frame, a shovel suspended from said frame, fluid actuated percussive means for driving 90 said shovel forward, means for raising and moving said shovel forwardly said means including a rigid arm and a flexible member, an automatic means to tilt and dump said shovel upon elevation to a predetermined 95 height.

2. An excavating machine comprising a frame, a shovel suspended from said frame, fluid actuated percussive means for driving 100 said shovel forward, means for raising and moving said shovel forwardly said means including a rigid arm pivoted to the said frame, and a flexible member attached to said arm and to said shovel and automatic means to tilt and dump said shovel. 105

3. An excavating machine comprising a frame, a shovel suspended from said frame, fluid actuated percussive means for driving 110 said shovel forward, means for raising and moving said shovel forwardly said means including a rigid arm pivoted to the said frame, and a flexible member attached to said arm and to said shovel and automatic means to tilt and dump said shovel, said means including a system of levers and links 115 cooperating with flexible means attached to said shovel handle.

4. An excavating machine comprising a frame, a shovel suspended from said frame fluid actuated percussive means for driving 120 said shovel forward, means for raising and moving said shovel forwardly said means including a rigid arm pivoted to the said frame, and a flexible member attached to said arm and to said shovel, automatic means to tilt and dump said shovel, said means including a system of levers and links 125 cooperating with flexible means attached to said shovel handle and flexible means attached to said frame and to the rear end of 130

said shovel handle for limiting longitudinal rearward movement of said shovel.

5. An excavating machine comprising a frame, a shovel suspended from said frame, fluid actuated percussive means for driving said shovel forward, pneumatic means for raising and moving said shovel forwardly, said means including a rigid arm pivoted to the said frame and a flexible member at-

tached to said shovel and said arm, a plunger extending into a cylinder of the said pneumatic means, said plunger automatically operated to cause automatic tilting and dumping of said shovel.

In testimony whereof I have signed this 15
specification.

CHARLES C. HANSEN.
